UNITED STATES PATENT OFFICE.

LEROY DRAKE, OF SHELTON, NEBRASKA.

CHURN.

SPECIFICATION forming part of Letters Patent No. 615,147, dated November 29, 1898.

Application filed January 12, 1898. Serial No. 666,485. (No model.)

To all whom it may concern:

Be it known that I, LEROY DRAKE, of Shelton, in the county of Buffalo and State of Nebraska, have invented a new and useful Improvement in Attachments for Revolving Churns, of which the following is a specification.

My invention is an improvement in the class of churning whose bodies are adapted to rotate or oscillate, whereby the cream is thrown alternately from one end to the other and caused to pass intermediately through a fixed reticulated diaphragm or partition for the purpose of quickly breaking the oily globules and inducing separation of the oil or butter from other constituents. I have devised an improved attachment for such churning which is in the nature of a diaphragm or partition adapted to be easily and quickly inserted and removed and to be secured in place in the body of a churn, as hereinafter described.

In the accompanying drawings, Figure 1 is a perspective view of a "barrel-churn" provided with my improved attachment. Fig. 2 is a plan view of my improved diaphragm or partition.

The barrel A is provided with trunnions a, as required, to adapt it for rotation in a suitable frame. My improved wooden diaphragm or partition is composed of segmental parts—namely, two semicircular parts B B', detachably connected by means of hooks and eyes b, applied to their straight edges.

The part B is provided with a series of openings c, separated by parallel transverse bars d. The other part B' is provided with a series of holes e. A bar or lever C is loosely hinged at one end f to the center of the semicircular part B' and is of such length that it extends half-way across the other part B, with which it may be detachably engaged by means of a button D. The latter is pivoted to one of the bars c and is undercut to adapt it to pass over the lever, as shown. The free end of the lever C rests on a short cross-bar d', which joins two of the aforesaid bars d. The circular edge of the diaphragm is provided with radial points g.

In order to insert and secure the collapsible diaphragm within the churn-body A, the

lever C is released from the button D, and the two parts B B' are adjusted and held together parallel at an angle to each other. In this position the diaphragm is placed in the barrel A and then expanded by bringing the parts B B' into parallelism horizontally, in which operation the points g enter sockets in the sides of the barrel A, and the lever C is pressed down flat upon said parts and locked by the button D, as shown. By this means the diaphragm is held firmly, yet detachably, in the churn-body A. When the latter is rotated on its trunnions a, the cream is thrown from one end to the other and back again, in which

operation it passes twice through the openings c and e in the respective parts B B', and thereby the oily globules are quickly broken by the numerous angular edges of the openings as well as by impact on the flat portions of the diaphragm, so that the cream is quickly converted into its main constituents, butter and whey. The removable diaphragm is thus a practically important and valuable improvement in churning of the class indicated, and being constructed of wood it may be so cheaply made as to be an inexpensive attachment.

What I claim is—

1. The improved collapsible diaphragm or partition for use within a churn of the class indicated, the same comprising two reticulated semicircular parts, which are flexibly connected, a locking bar or lever, and means for securing it in place on the said parts and thereby holding them rigidly in the same plane, substantially as shown and described.

2. The improved collapsible diaphragm or partition for use within a churn of the class indicated, which comprises two reticulated semicircular parts flexibly connected, a lever hinged to one of said parts, and a device attached to the other part and adapted for locking engagement with the free end of the lever, substantially as shown and described.

3. The improved collapsible diaphragm or partition for use within a churn of the class indicated, which consists of two flat semicircular parts having openings and flexibly connected at their adjacent straight edges, a lever hinged to one of such parts, and a pivoted locking device on the opposite parts for

locking the free end of the lever and thereby holding said parts in rigid alinement, substantially as shown and described.

4. The combination with a churn-body of a collapsible diaphragm or partition arranged within said body comprising segmental parts flexibly connected and having peripheral points as specified, and a lever hinged on one of said parts, and means for detachably locking its free end to the other part, substantially and shown and described.

5. The combination with a churn-body of the diaphragm formed of two hinged foldable parts, and a lever and a locking device applied thereto, said diaphragm being arranged in the churn-body, as and for the purpose specified.

LEROY DRAKE.
